UNITED STATES PATENT OFFICE.

PHILIP FRITZ, OF GRAND RAPIDS, MICHIGAN.

ICE-CREAM CABINET.

Application filed May 18, 1925. Serial No. 30,895.

To all whom it may concern:

Be it known that I, PHILIP FRITZ, a citizen of the United States of America, residing at Grand Rapids, in the county of Kent and State of Michigan, have invented certain new and useful Improvements in Ice-Cream Cabinets; and I do hereby declare the following to be a full, clear, and exact description of the invention, such as will enable others skilled in the art to which it appertains to make and use the same.

This invention relates to an ice cream cabinet, being particularly concerned with novel improvements in cabinets wherein containers for ice cream may be housed and the same with their contents kept in refrigerated condition.

In cabinets of this character, the refrigerant used in a great many instances is ice with salt applied thereto, it being well known that such mixture of ice and salt produces a low temperature and one at which ice cream or the like may be kept in solid frozen condition. One feature of my invention is directed to a protective means for the lining of the cabinet. The lining of sheet metal is very susceptible to the corrosive action of salt water and of moisture condensing thereon and unless said lining is protected it rusts through very rapidly; and it is one of the primary objects and purposes of the present invention to make a cabinet wherein the sheet metal lining therefor is protected positively against the corrosive action of the brine produced from the refrigerating mixture or from oxidizing due to moisture condensing thereon.

Another feature of the invention relates to a simple and effective means for holding the mixture of ice and salt whereby the same may be held in receptacles which are filled outside of the store in which the cabinet is used, and then carried in and applied to the cabinet at either side of the ice cream containers. This is a feature of value making it possible to avoid the carrying of broken ice and salt separately into the store and placing in the cabinet, all handling of the ice and salt being accomplished outside of the store and the undesirable conditions incident thereto avoided.

For an understanding of the invention by means of which these ends are effectively attained, reference may be had to the follow-

ing description taken in connection with the accompanying drawing, in which—

Fig. 1 is a vertical transverse section through the cabinet.

Fig. 2 is a plan view thereof, the covers for the ice cream cans and those covering the refrigerant holding receptacles being removed.

Fig. 3 is a perspective view of the cabinet, the covers over the refrigerant holding receptacles being removed, and

Fig. 4 is a perspective view of one of the receptacles used for holding the refrigerant which, as stated, may consist of broken ice and salt.

Like reference characters refer to like parts in the different figures of the drawing.

In the construction of the cabinet an elongated receptacle 1 of rectangular form is provided having an open upper end around which an open frame 2 is placed. The cabinet is partly filled with suitable insulation material indicated at 3 which may be of cork or the like, the same being disposed between the sides, ends and bottom of the cabinet and the sheet metal lining which is located inside said cabinet. This lining consists in the construction shown of downwardly and inwardly extending sides 4 which, at their lower edges, are turned inwardly toward each other to make horizontal bottom sections 5, are then turned downwardly so as to extend vertically making the sections 6, the lower edges of which are connected by a central bottom section 7. The lining is of sheet metal and around its upper edges is formed with outwardly extending horizontal continuous lips 8 which extend between retaining bars 9 and 10 one above and the other below said lips and which are secured in place in any suitable manner to the sides and ends of the cabinet and the frame 2 as shown. The sheet metal lining is coated on its outer side with a covering of asphalt pitch 11 preferably, though it is to be understood that any other protective covering of this kind which will exclude water and moisture from the metal may be used as an equivalent. The inner sides of the lining are also covered with the same material, as indicated at 12. In this manner the lining is impervious to the action of either water or brine and will

not rust and deteriorate the same as though uncovered. This is valuable though the ice and salt may not be placed loosely in the cabinet around the ice cream receptacles as the lowering of the temperature within the cabinet is likely to produce condensation of moisture against the metal on both sides without any direct contact of moisture to the lining such as occurs in many cases where the cabinet is saved by placing the ice and salt directly in the cabinet and not in the holding receptacles, as shown in the present construction.

In order to protect the inner side of the lining and keep the pitch from being accidentally scratched or scraped off so as to expose the metal, said inner sides of the lining and the pitch coating 12 thereon are covered with strips of wood. For instance the sides 4 of the lining are covered by the wood members 13, at the inner sides of the sections 5 are the wood members 14 and at the inner sides of the sections 6 and 7 the wood members 15 and 16. In practice these members 13, 14, 15 and 16 cover the metal sufficiently that the asphaltic pitch 12 on the inner side of the lining is not reached and injured either by sharp pieces of ice or by the one packing the ice in the cabinet when he breaks and forces down the ice, usually using a stick which is operated as a ram to pack and force the ice into the cabinet. This is a valuable feature of the invention, for with the metal covered and protected by the asphalt covering and said covering safeguarded against injury the metal lining is safe from deterioration due to the corrosion and oxidization to which it is particularly subject when exposed to moisture and especially to moisture combined with common salt.

The cans 17 for holding the ice cream, at their lower ends pass into the well of the cabinet which is formed by the vertical sides 15 and the base 16, there being spaces at each side of the cans above the parts 14 as is evident. Over the cans and longitudinally of the cabinet a frame is located having ends 18, spaced side bars 19 and cross bars 20, said cross bars 20 being located between adjacent cans at their upper ends. A cover 21 may be applied to this frame over the upper end of each ice cream holding receptacle 17 so that only the single cover needs to be removed whenever access to a particular ice cream can is desired.

The spaces between the cans and the sides 13 are designed to be filled with the refrigerant which can be applied loosely in these spaces, the broken ice and salt being packed therein but, preferably, suitable deep receptacles 22 designed to fit the spaces are used in which the ice and salt may be packed outside of the store and then carried in and inserted in the spaces between

the cans and the sides of the cabinet. When thus applied covers 23 are placed over the upper end of the refrigerant holding receptacles. In order that the receptacles 22 may be readily carried a cross bar 24 between the sides of each receptacle is used to serve as a handle to carry the same.

The construction of the ice cream cabinet described is particularly practical and efficient and has so proved in service. The safeguarding of the lining against deterioration adds materially to the length of life of the cabinet while the simple and effective manner of applying the refrigerant in the cabinet is a feature of great value particularly from the standpoint of sanitation. The icing of the cabinet is accomplished outside of the store and the ice and salt there placed together and within the refrigerant holding receptacles, there being no breaking of ice and scattering of ice and salt adjacent the cabinet and the floor on which it is placed in the store as takes place when the icing of such cabinets is done within the store. With my invention the icing is accomplished outside of the store and the receptacles need merely be carried in and placed in the cabinet. In addition where receptacles of this type are used to hold the refrigerant of ice and salt no faucet is needed in connection with the cabinet to draw off the liquid which comes from melting ice and the dissolving of the salt in the water thus produced. Faucets of this character are not only subject to very rapid deterioration, requiring frequent replacement, but are liable to collect deposits of unsanitary nature, all of which is obviated with my invention. The invention is defined in the appended claims and is to be considered as comprehensive of all forms of structure coming within their scope.

I claim:

1. In a construction of the class described, a cabinet having sides and ends and an interior space adapted to receive ice cream holding containers, said space at the lower portion thereof being relatively narrow and of a width to receive a single ice cream container and of a length to receive a plurality thereof, and at its upper portion being widened whereby an elongated space is left between a side of the cabinet and containers for ice cream placed therein, and a plurality of refrigerant holding receptacles located end to end in said last mentioned space and adapted to be freely placed therein or removed therefrom.

2. In a construction of the class described, a cabinet having sides and ends and an elongated interior space in which ice cream holding containers are adapted to be placed, said space at its lower portion being in the form of an elongated relatively narrow rectangular well and at its upper portion being

- widened at both sides of the well whereby elongated spaces are left between ice cream containers placed in alinement in the well and the inner sides of the cabinet, and a plurality of refrigerant holding receptacles located end to end in each of said last mentioned spaces at each side of and above the well and adapted to be freely placed therein or removed therefrom.
- 10 3. In a construction of the class described, a cabinet having sides and ends and an interior space, said space at its lower portion comprising a relatively narrow and elongated rectangular well and at its upper portion being widened, a plurality of ice cream containers of substantially cylindri-
- cal form located in said interior space of the cabinet with their lower portions received in said well and with their upper portions spaced from an inner side of the cabinet, and a plurality of refrigerant holding receptacles located between the said inner side of the cabinet and the upper portions of said containers, each of said receptacles being freely removable from the cabinet independently of any other receptacle or of any ice cream container, and freely placed therein, substantially as described.
- 15 In testimony whereof I affix my signature.

PHILIP FRITZ.
